United States Patent [19]

Hara

[11] Patent Number: Des. 297,435

[45] Date of Patent: ** Aug. 30, 1988

[54] ELECTRONIC COPYING MACHINE

[75] Inventor: Kunio Hara, Chiba, Japan

[73] Assignee: Kabushiki Kaisha Toshiba, Kawasaki,
Japan

[**] Term: 14 Years

[21] Appl. No.: 806,411

[22] Filed: Dec. 9, 1985

[30] Foreign Application Priority Data

Jun. 10, 1985 [JP] Japan 60-24010

[52] U.S. Cl. D16/31

[58] Field of Search D16/27-32;
355/3 R, 3 SH, 5-11, 14 R, 14 SH, 18-19, 51

[57] CLAIM

The ornamental design for an electronic copying ma-
chine, substantially as shown.

DESCRIPTION

FIG. 1 is a front, top and right side perspective view of
an electronic copying machine showing my new design;
FIG. 2 is a perspective view like FIG. 1 with the cover
in an open position;

FIG. 3 is a top plan view thereof;

FIG. 4 is a front elevational view thereof;

FIG. 5 is a right side elevational view thereof;

FIG. 6 is a rear elevational view thereof;

FIG. 7 is a left side elevational view thereof; and

FIG. 8 is a bottom plan view thereof.
